UNITED STATES PATENT OFFICE.

MARY L. LEIGH, OF NORFOLK, VIRGINIA.

DESIGN FOR A MAP.

No. 33,266.

Specification for Design.

Patented Oct. 2, 1906.

Application filed August 31, 1906. Serial No. 332,872. Term of patent 3½ years.

To all whom it may concern:

Be it known that I, MARY L. LEIGH, a citizen of the United States, residing at Norfolk, in the county of Norfolk and State of Virginia, have invented a certain new, original, and ornamental Design for a Map, reference being had to the accompanying drawing, which shows a plan view of the map.

I claim—

The ornamental design for a map as shown.

MARY L. LEIGH.

Witnesses:

ANTONIO J. SMITH,
WALTER B. BURROW.
